UNITED STATES PATENT OFFICE.

CHARLES C. ROSE, OF SCRANTON, PENNSYLVANIA.

COAL-STOCK TRESTLE.

SPECIFICATION forming part of Letters Patent No. 414,725, dated November 12, 1889.

Application filed March 20, 1889. Serial No. 304,046. (No model.)

To all whom it may concern:

Be it known that I, CHARLES C. ROSE, a citizen of the United States, residing in Scranton, in the county of Lackawanna and State 5 of Pennsylvania, have invented certain new and useful Improvements in Gates for Coal-Stock Trestles, of which the following is a specification.

My invention consists in certain new and 10 useful improvements in gates for coal-stock trestles, and will be fully and clearly herein-after described and claimed, reference being had to the accompanying drawings, in which—

Figure 1 represents a sectional elevation of 15 a coal-holding bin, showing a side elevation of my invention connected therewith, and an end view of a car in position for receiving a load of coal therefrom. Fig. 2 is a side elevation showing a slight modification of the operating 20 mechanism for opening or closing the gate. Fig. 3 is a detached front elevation of the gate. Fig. 4 is a detached front elevation of the grooved pulleys connected with the operating mechanism.

25 The object of my invention is to produce a gate for coal-trestles or for other similar purposes that can be easily operated or opened or closed by hand. Heretofore it has been very difficult to operate such gates, owing to 30 the great vertical pressure of the coal or other equivalent material upon the gate. This objection I overcome by locating my gate in such a position as to relieve it almost entirely from the perpendicular pressure produced by 35 the weight of the material resting upon it, and so that it is subjected to a slight lateral pressure only.

In said drawings, 1 represents an ordinary coal-bin, which may be of any well-known 40 form or size. At the bottom of the bin is an inclined opening or chute, in which the gate 2 is mounted on a shaft 3 in suitable bearings at the end of the inclined chute, in such position as to relieve it from the vertical 45 pressure of the coal. (See Fig. 1.) The face 4 of the gate is in the form of an arc of a circle whose center is the shaft 3, and as it is located to one side, under or nearly under the floor or plate 5, it is subjected to very little pressure, and can be easily turned to open

or close it by hand. To the upper rear portion of the gate are two projecting lugs 6, and between them is pivoted the end of a rod 7 (see Figs. 1 and 3) by a pin 8, having its opposite end pivoted to the end of an angular 55 arm 9 by a pin 10. This arm 9 is mounted on a shaft or pin 11, so as to turn easily, and is secured in any well-known way to the under side of the coal-bin—to the beam 12, for instance. A double-grooved pulley 13, having grooves *a* and *b*, is mounted on a shaft 14, (see Figs. 1 and 4,) and secured so that its periphery will be in or nearly in a vertical line with the opposite end 15 of the arm 9. (See Fig. 1.) To the pin 10 (or to that 60 end of the arm) is secured the end of the chain 16, which passes over the pulley 13 in one of its grooves, and then, passing down vertically far enough to be within convenient reach of the operator's hand, is provided 65 with a hand-stirrup 17. To the end 15 of the arm 9 is secured another chain 18, which passes up and over the pulley 13 in its other groove, and then passing down is provided 70 with a hand-stirrup 19 for operating it. From 75 this construction it will be seen that a pull downward on the stirrup 17 will move the rod 7 in the direction of the arrow *V* and turn the gate in the position shown by the dotted lines 20, (see Fig. 1,) and thereby open it and 80 permit the coal or other material to flow out into the car, as shown, after which a pull on the stirrup 19 will reverse the operation and close the gate or bring it into the position shown in Fig. 1.

In the modification shown in Fig. 2 the arm 9 is dispensed with and the chains 16 and 18 are secured directly to the bar or rod 7. The chain 16 passes up over in one groove of the pulley 13, and is secured to a lug 21 on the 90 bar 7, and the chain 18 passes up over from the other side of the pulley 13 in the other groove, and is connected by a lug 22 on the rod 7. From this construction it will be obvious that the rod 7 may be moved longitudinally back and forth by pulling on the hand-stirrups 17 and 19. In this case the rod 7 would have to be supported in slideways 23 95 24 or the equivalent thereof.

The sides of the gate are provided with a 100

series of openings 25, to decrease its weight as much as possible consistent with the required strength.

I claim as my invention—

5 A bin provided with a gate for coal-stock trestles, said gate consisting of a curved-face pivoted gate located in an inclined chute, so as to bring it under or substantially under the floor of the coal-bin and away from the 10 vertical pressure of the coal, in combination with mechanism for opening or closing it, consisting of a double-grooved pulley, a rod

pivoted to the gate, and chains having hand-stirrups at their lower ends for operating them, and their upper ends passing over the 15 pulley in opposite grooves and in opposite directions and connecting with the rod secured to the gate for opening and closing it, substantially as described.

CHARLES C. ROSE.
